Primary Examiner — Ryan Harvey*(74) Attorney, Agent, or Firm* — POLSON
INTELLECTUAL PROPERTY LAW, PC; Margaret
Polson(57) **CLAIM**

The ornamental design for a machine for game of chance, as shown and described.

DESCRIPTION

FIG. 1 is a side perspective view of my new design for a machine for game of chance.

FIG. 2 is a front elevation view of FIG. 1.

FIG. 3 is a back elevation view of FIG. 1.

FIG. 4 is a right side elevation view of FIG. 1.

FIG. 5 is a left side elevation view of FIG. 1.

FIG. 6 is a top plan view of FIG. 1; and,

FIG. 7 is a bottom plan view of FIG. 1.

The features shown in broken lines in the drawing depict disclaimed subject matter only and form no part of the claimed design.

1 Claim, 5 Drawing Sheets(56)
